UNITED STATES PATENT OFFICE

128,156

DESIGN FOR AN INSIDE FOOTPAD SOCK

Albert E. Berger, Atlantic City, N. J.

Application January 9, 1941, Serial No. 97,909

Term of patent 3½ years

To all whom it may concern:

Be it known that I, Albert E. Berger, a citizen of the United States, residing at Atlantic City, in the county of Atlantic, State of New Jersey, have invented a new, original, and ornamental Design for an Inside Footpad Sock, of which the following is a specification, reference being had to the accompanying drawing, forming part thereof.

The figure is a top perspective view of an inside footpad sock showing my new design.

I claim:

The ornamental design for an inside footpad sock, as shown.

ALBERT E. BERGER.
